PREFORMED NECKTIE

Willie Moore Livingstone, 51 Cambridge Place,
Brooklyn, N.Y.

Filed Mar. 7, 1962, Ser. No. 69,268

Term of patent 14 years

(Cl. D3—16)

FIG. 1

FIG. 2

FIG. 3

FIG. 1 is a front elevational view of a preformed necktie showing my new design with parts thereof being shown broken away for convenience of illustration;
FIG. 2 is a side elevational view thereof; and
FIG. 3 is a rear elevational view thereof.
I claim:
The ornamental design for a preformed necktie, as shown and described.
